UNITED STATES PATENT OFFICE.

JOHN I. McDONALD, OF ST. JOSEPH, MISSOURI.

REVERSIBLE CUFF.

Application filed December 6, 1923. Serial No. 678,956.

To all whom it may concern:

Be it known that I, JOHN I. McDONALD, a citizen of the United States, residing at St. Joseph, in the county of Buchanan and State of Missouri, have invented certain new and useful Improvements in Reversible Cuffs, of which the following is a specification.

This invention relates to attached shirt 10 cuffs of the folded or "French" variety and to the type of such cuffs known as "reversible" because the extreme half of the cuff may be worn folded either outwardly or inwardly and in either position the appearance 15 of the cuff remains the same.

The present cuff is complete on both sides, both its faces being finished alike. Preferably, as in this case, it contains one ply of interlining but this may be omitted or 20 there may be additional plies if desired.

The complete cuff is attached to the sleeve 25 of the shirt by a "fly" or intermediate strip which is stitched to the lowest ply of the cuff, that is, to the ply next to the arm when the cuff is folded outwardly; or it may be stitched if desired, through that ply and the interlining.

Buttonholes for the cuff links or fasteners 30 are provided at proper points to register when the cuff is folded in either position and to hold the cuff closed.

In the accompanying drawings:

Figure 1 is a perspective view showing the cuff attached to a shirt sleeve and in its 35 usual arrangement.

Fig. 2 is a similar view showing the cuff reversed.

Fig. 3 is a section on the line 3—3, Fig. 1; and

Figs. 4 and 5 are opposite views of the 40 unfinished, partially stitched cuff, laid out flat, certain parts being shown as folded back to expose the construction and arrangements of plies, interlining, and fly.

The cuff has inner and outer pieces or 45 plies of cloth 1, 2, usually of the same material as the shirt, a piece of whose sleeve appears at 3.

As illustrated, the plies 1 and 2 are each 50 of a single thickness, and they are duplicates, being provided with rounded or square corners as desired.

Interlining 4 is provided which, as shown, 55 comprises a single ply but additional plies could be used if desired.

The plies 1, 2, and interlining 4 are preferably pressed into shape together, the edges of plies 1 and 2 being folded inwardly and crimped as at 5.

The three or more pieces thus described 60 then go to the stitcher who removes the outer piece which becomes the ply of the cuff next to the wearer's wrist and reverses it, placing it upon the other piece with the interlining inside, which latter arrangement 65 is as shown in the drawings. It is only necessary then to stitch around the folded in and crimped edges of the plies and interlining. However, prior to this stitching operation, the single piece first removed has 70 had stitched to it the fly 7.

The stitching connecting the plies 1, 2, and interlining 3, appears at 8. The stitching connecting the fly 7 is shown at 9.

The fly 7 is preferably a folded piece of 75 the same material as the shirt and cuff, with folded in longitudinal edges 10, said fly being stitched at 9 to the inner ply 1 of the cuff along the folding line of said fly. The line of stitching 9 is disposed away from 80 the inner margin of the ply 1.

After the stitching of the fly 7 to the 85 ply 1 has been accomplished, the plies 1 and 2 are stitched together at 8, as previously described.

The cuff is then provided with buttonholes 11 in the reversing half of the cuff 90 registering with corresponding buttonholes 12 in the half of the cuff to which the fly is attached. The buttonholes 12 are preferably located beyond the line of stitching 9.

The complete cuff is now ready for attachment to the sleeve 3. By referring to Fig. 4, it will be observed that the fly 7 is left open so that the end of the sleeve 3 95 may be inserted therein. This having been accomplished, the fly 7 is stitched to the end of the sleeve 3 by the stitching 13.

The folding line of the cuff appears at 14.

In the claims, the word "finished" has 100 reference to an edge, formed in any manner, making it other than a "raw" edge; similarly, the word "fold-over" is intended to define adaptability for folding on top of, or under, when reversing the cuff, so that 105 one part of the cuff is in superposed relation to the remaining part thereof, as in "French" cuffs.

I claim:

1. A reversible, fold-over cuff provided 110

with a fly secured thereto nearer one end of the cuff than the other end thereof, said fly being composed of plies which are finished at their free edges but left open to form a mouth adapted to receive, and to conceal, the raw edge of the shirt sleeve when the cuff is being attached to said sleeve.

5 2. The method of making a reversible fold-over cuff, consisting in stitching together foldable plies to form a fold-over cuff, separately forming a multi-ply fly having a finished edge and an open, finished

mouth, and securing said fly to said cuff nearer one end of the cuff than the other end thereof in such manner as to hinge the fly 15 to the cuff along one of the edges of the fly and to leave the mouth of the fly in the free part thereof so that said mouth will be adapted to receive, and to conceal, the raw edge of a shirt sleeve when the cuff is being attached to said sleeve.

10 In testimony whereof I affix my signature.

JOHN I. McDONALD.
